US0D1052351S

(12) **United States Design Patent** (10) **Patent No.:** **US D1,052,351 S**
(45) **Date of Patent:** **** Nov. 26, 2024**

(54) **CUP RACK**

(71) Applicant: **SHENZHEN JINCHANNEL INNOVATION TECHNOLOGY CO., LTD.**, Shenzhen (CN)

(72) Inventor: **Enqun Li**, Shenzhen (CN)

(73) Assignee: **SHENZHEN JINCHANNEL INNOVATION TECHNOLOGY CO., LTD.**, Shenzhen (CN)

(**) Term: **15 Years**

(21) Appl. No.: **29/958,649**

(22) Filed: **Aug. 21, 2024**

(51) **LOC (14) Cl.** **07-09**

(52) **U.S. Cl.**

USPC **D7/600.1**

(57) **CLAIM**

The ornamental design for a cup rack as shown and described.

DESCRIPTION

FIG. 1 is a perspective view of a cup rack showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 shown in FIG. 2. The dash-dash broken lines in the drawings depict portions of the cup rack that form no part of the claimed design. The dot-dash broken lines in FIGS. 2 and 9 represent boundaries of the enlarged portions and form no part of the claimed design.

1 Claim, 9 Drawing Sheets
